CYRUS J. PARKER, OF PORTLAND, OREGON; MARY E. PARKER, EXECUTRIX OF SAID CYRUS J. PARKER, DECEASED, ASSIGNOR TO IRON FIREARM MANUFACTURING COMPANY, OF PORTLAND, OREGON, A CORPORATION

ROUND TUYÈRE FOR FURNACES

Application filed May 16, 1927. Serial No. 191,606.

This invention relates generally to coal burning furnaces, and particularly to the under feed type of furnace in which fuel is fed upwardly into the fire box by a worm and 5 air is supplied to the piston by means of a fan.

The first object of this invention is to provide an exceedingly simple and efficient form of circular fire pot from which air can escape in three varying degrees of intensity and volume for the purpose of furnishing the strongest blast during the early stages of combustion and the lightest blast when the fuel is almost entirely consumed.

The second object is to provide the maximum amount of air to the combustion without danger of carrying over incompletely burned particles of fuel with the blast.

The third object is to so completely burn the fuel that there will be practically an entire elimination of soot or smoke.

The fourth object is to so construct the tuyères that they will develop an intense heat sufficient to fuse the incombustibles into an easily removable clinker which is worked 25 up on top of the burning coals by the oncoming fuel.

The fifth object is to so construct the tuyères that they can be easily installed in various sizes of furnaces and permit the use 30 of encircling fire brick which protect the interior of the furnace from the direct blast of the tuyères.

These, and other objects, will become more apparent from the specification following as 35 illustrated in the accompanying drawings, in which:

Figure 1 is a vertical section through the circular fire pot and the lower portion of a furnace taken along the line 1—1 in Figure 40 2 and also breaking away a portion of the hopper to show the parts behind same. Figure 2 is a partial plan view and horizontal section taken along the line 2—2 in Figure 1. Figure 3 is a perspective view of a 45 single tuyère. Figure 4 is a vertical section through the fire box of the furnace taken perpendicularly to Figure 1 and showing the fuel bed and its relation to the tuyères.

Similar numbers of reference refer to similar parts throughout the several views.

Referring in detail to the drawings, in order to illustrate this invention there is shown the outer casing 10 and the inner wall 11 of a furnace which is set on the base ring 12. Within the inner wall 11 and resting on the 55 floor 13 is a hopper 14 through which coal is fed upwardly by the screw 15 in any convenient manner. Around the hopper 14 is a wall 16 whose upper edge 17 is inturned to the level of the top of the hopper 14, leaving an opening between same for the upward passage of air through the air passage 18.

The three tuyères are arranged to form the walls of a circular fire pot whose inner wall 19 converges downwardly to correspond with the discharge opening of the hopper 14. The outer wall 20 of each tuyère is vertical and has formed therein a groove 21 adapted to receive a curved supporting plate 22 sufficiently narrow to permit easy assembling and 60 having formed at the ends thereof the pockets 23 through whose sides are passed the bolts 24.

The plates 22 have a double function, first to hold the tuyère sections together and second to support the fire brick lining 25 which projects somewhat above the top 26 of the tuyères. In the top 26 is formed a channel 27 provided with a raised cover 28 having inwardly facing openings 29 which are somewhat larger than the outwardly facing openings 30.

Across the bottom of each tuyère is formed a floor 31 having a downturned flange 32 near whose ends are formed the inwardly projecting lugs 33 which engage the rim 34 of the hopper 14.

Between the flange 32 and the wall 19 is formed a curved opening 35 through which air enters into the compartment 36 formed within the tuyère. Each tuyère is provided with closed ends 37. Near the top of the wall 19 are formed the openings 38 which openings are relatively long and through which escapes the major portion of the air 90 into the burning coals.

In the floor 39 of the channel 27 is formed a number of openings 40 whose area is such as to restrict the flow of air into the channel 27, that is, the total area of all of the holes 95 100

29 and 30 is greater than the total area of all of the holes 40.

In operation, fuel 41 is fed up into the fire pot by the screw 15 and first comes in contact 5 with a relatively strong inwardly directed draught indicated by the arrows 42. As it increases in temperature and inflammability it is pushed upwardly by the oncoming fuel past the openings 29 where a second inwardly directed blast of somewhat less volume and pressure is directed against same, as indicated by the arrows 43.

It must be borne in mind that as the burning 15 of the fuel nears completion it rapidly loses weight and as it is gradually worked over the cover 28, which is the highest point of the tuyère, it falls into the circular channel 44 just inside of the fire bricks 25 where the softest blast of air completes the burning 20 process. The intense heat generated by the combustion melts the incombustibles into curved clinkers following the general shape of the tuyère, which clinkers are always on top of the fuel bed from which they can be 25 easily removed by suitable tongs.

Where furnaces of greater dimensions are encountered it is only necessary to use a plate 22 of greater width which will sustain larger or more fire brick 25 to fill in the space between the wall 20 and the wall 11.

I am aware that many forms of tuyères have been constructed in the past; I therefore do not claim same broadly but I do intend to cover all such forms and modifications thereof as fall fairly within the following claims:—

I claim:

1. A fire pot for underfed stokers consisting of a plurality of hollow curved tuyère 40 sections joined in circular form having a groove formed around the outer side of same, each section having a main chamber and an auxiliary chamber communicating therewith, said main chamber having inlet and outlet 45 openings, said auxiliary chamber having unequal outlet openings on opposite sides thereof, an annular sectional plate having its inner edge lying within said groove, and means for clamping the sections of said plate together.

2. A hollow arcuate tuyère member having a main air chamber and an auxiliary air chamber in communication therewith through a plurality of openings, said member being 55 adapted to form a section of an underfed stoker retort, with said auxiliary chamber above the main chamber, said lower chamber having an air outlet opening into the retort, said upper chamber having outlet openings 60 exceeding the area of the openings between said chambers.

3. A hollow arcuate tuyère member having a main air chamber and an auxiliary air chamber in communication therewith 65 through a plurality of passages, said mem-

ber being adapted to form a section of an underfed stoker retort, with said auxiliary chamber above the main chamber, said lower chamber having outlet openings through its fuel-engaging side, said upper chamber having outlet openings on opposite sides thereof discharging toward and away from the center of the retort, the outwardly pointing openings having less area than do the corresponding inwardly pointing openings, the area of the combined lower chamber outlets and the area of the combined upper chamber outlets each exceeding the area of the combined passages between the upper and lower chambers.

4. A hollow arcuate tuyère member having a main air chamber and an auxiliary air chamber in communication therewith, said member being adapted to form a section of an underfed stoker retort, with said auxiliary chamber above the main chamber, said arcuate member having an upright outer wall, a sloping inner wall and horizontal top, bottom and dividing members, said dividing member separating the main air chamber from the auxiliary air chamber, said main chamber having horizontal slots through said sloping wall near said dividing member, said auxiliary chamber having horizontal slots through the inner and outer sides thereof above said dividing member, said dividing member having openings therein which are less in total area than either the lower chamber outlets or the upper chamber outlets.
